UNITED STATES PATENT OFFICE.

STANLEY L. FISHER, OF CHESTER, CONNECTICUT, ASSIGNOR TO PRATT READ PLAYER ACTION COMPANY, OF DEEP RIVER, CONNECTICUT.

PLAYER PIANO.

Application filed October 23, 1920. Serial No. 418,879.

To all whom it may concern:

Be it known that I, STANLEY L. FISHER, a subject of the King of Great Britain, residing in Chester, county of Middlesex, State of Connecticut, have invented certain new and useful Improvements in Player Pianos, of which the following is a full, clear, and exact description.

My invention relates to player pianos and more particularly to the provision of a pneumatic action of improved operation and to improved means for transmitting the power of the player pneumatics to the piano action.

When a pneumatic player action is inserted in a piano, a certain amount of adjustment is required between the striker arm of the pneumatic action and the members of the piano action with which these arms engage. Also, the striker arms themselves must, at times, be adjusted so that they will properly "line up" or lie in a single horizontal plane. Heretofore these adjustments have been difficult to make and the result is that the striker arms do not occupy the proper positions relatively to the piano action units with which they cooperate. An improper attack of the striker pneumatic upon the piano action results when these objectionable features are present.

One object of my invention is to provide an improved pneumatic action for player pianos wherein these disadvantages are overcome.

Another object of my invention is to provide an improved connection between the pneumatic action and the piano action.

A further object of my invention is to provide adjustable one piece striker arms for the player pneumatics.

A still further object of my invention is to provide flexible, resilient striker arms adapted to be attached to the player pneumatics at one end and to engage the piano action at the other end to actuate the same.

A still further object of my invention is to provide a resilient and flexible striker arm which may be rigidly attached to the striker pneumatic so that the usual striker arm guide rail may be dispensed with.

To these and other ends the invention consists in the novel features and combinations of parts to be hereinafter described and claimed.

In the accompanying drawings:

Fig. 1 is a side elevational view, partly in section, of an action unit embodying my invention;

Fig. 2 is a rear elevational view of a part of the pneumatic action detached from the piano action.

Fig. 3 is a plan view on line 3—3 of Fig. 1.

Fig. 4 is a view similar to Fig. 1, but showing a modified form of my device in which the striker arms contact with the wipers.

Fig. 5 is a sectional view on line 5—5 of Fig. 4.

Fig. 6 is a bottom plan view of one of the striker pneumatics of the upper tier.

Fig. 7 is a view similar to Fig. 6 of a pneumatic of the lower tier.

Fig. 8 is a detail view of a striker pneumatic of each tier, the striker arms being shown in adjusted positions in dotted lines.

In the embodiment of my invention shown in Figs. 1 to 3, I have shown a piano action of a conventional type, comprising a hammer 10, which is pivoted at 11 to the rail 12, and is adapted to be moved forwardly by the jack 13 to strike the string 14 to sound a note. At the lower side of the rail 12 is pivoted at 15 a wippen 16 to which the jack 13 is pivoted and by which the jack is operated. The abstract 17 is pivoted to the wippen at 18 and extends downwardly to a position above the usual piano keys (not shown). In the usual 90 operation of the parts thus far described, when the front end of a key is depressed, the abstract 17 is raised thus by means of the jack 13 forcing the hammer toward the string. The piano action described is not 95 a novel feature of the invention and any suitable action may be used with my improvements.

The pneumatic action shown in Fig. 1 consists of a wind chest 19 provided with an extension 20 carrying the pneumatic action rails 21 and 22, which are provided with the ducts 23 and 24 leading to the valve chest (not shown), which is embodied in the pneumatic action 19.

The particular arrangement of the valves in the valve chest and the ducts supplying the same with their motive fluid is of no particular importance as far as this invention is concerned, but the arrangement shown 110

in my Patent No. 1,329,702, granted February 3, 1920, may be used advantageously. A tracker bar is shown in a more or less diagrammatic and conventional way at 25, and a tracker duct is shown at 26 leading from the tracker bar to the pneumatic action. The pneumatic action rails 21 and 22 are each provided on their lower surfaces with a row or tier of striker pneumatics, those secured to the upper rail, being designated by the numerals 27, and those secured to the lower rail by the numerals 28. While I have shown my pneumatic action provided with two tiers of striker pneumatics, it is to be understood that I do not propose to be limited to this exact arrangement, for it might be found desirable to provide more than two tiers of striker pneumatics, or it may be found desirable to provide only one tier of the same. In either case the arrangement may be secured by simply providing the number of pneumatic action rails desired and supplying the same with the desired number of striker pneumatics. A stop rail 29 is carried by the fixed leaves of the pneumatics 27, and is provided with a series of stop buttons 30, which are provided with threaded shanks or stems 31 screwed into the rail 29. The positions of the buttons 30 may by means of the threaded shank 31 be adjusted within certain limits. Brackets 32 are attached to abstracts 17 and these brackets are provided with the contact buttons 33, carried by the threaded stems 34, which are adjustably engaged with the brackets 32. The movable leaves of the pneumatics 27 are provided with striker arms in the form of flat metallic lug members 35 and the pneumatics 28 are provided with striker arms in the form of the metallic members 36. In order that the striker surfaces of the striker arms of the pneumatics of each tier may be in the same plane, the striker arms 36 consist of a substantially horizontally disposed base portion 37, which is adapted to be attached to the movable leaf of the pneumatic 28, a vertically extending portion 38, which terminates in a horizontally disposed bent-over portion 39, which serves to contact with the lower surface of the button 33. These striker arms are bent into this shape from a single flat piece of metal. The striker arms 35 attached to the pneumatics 27 extend horizontally from the lower movable leaves of the pneumatics and the extended ends 40 contact with the lower surfaces of the buttons 33 of the corresponding piano actions. The arms 35 and 36 are made of what might be termed spring metal, which while rigid enough to maintain its shape and position while in use, is resilient enough to somewhat relieve the shock of the blows delivered by the striker pneumatics, and is flexible enough to be bent slightly in order to adjust the striking surfaces of the

arms to their proper positions. In case the striking surfaces of the arms do not properly line up and the surfaces do not lie in a horizontal plane as they should, these arms may be bent by a proper tool so as to vary the positions of the striking surfaces of the same. The positions which may be assumed by the arms so bent are shown in dotted lines in Fig. 8. This provides a very simple, convenient and satisfactory method of adjusting these arms, which very often in the assemblage of the pneumatic action will be found to be out of their proper positions. The metal of which the arms are made is, as stated, sufficiently rigid so that they will not be bent out of position by the force of the stroke of the pneumatic against the piano action. These striker arms 35 and 36 are rigidly secured to the lower leaves of the striker pneumatics, so that they will be guided in their movements by these leaves and a separate guide means or guide rail, such as is usually used with the pneumatic striker arms, may be dispensed with. The modified form of my invention shown in Figs. 4 and 5 differs from the structure just described only in providing a wippen attack for the striker pneumatics instead of an attack on the abstract, as shown in Fig. 1. To accomplish this, the pneumatic action 19 is placed in a higher position in the piano in the form shown in Fig. 4, so that the striker pneumatics 27 and 28 will occupy a position nearer the wippens 16, as shown, also in this form in this embodiment of my invention, the front end of the wippen is extended slightly as at 41 and a contact button 42 is secured to this extended end by a threaded shank or stem 43, which may be adjusted in the wippen to vary the position of the button. The pneumatic action is then placed in the instrument so as to occupy the same position relative to the wippens and the contact buttons 42, as previously described in the case of the bracket 32 and the buttons 33. The remaining parts of the piano action and the pneumatic action, including the striker arms 35 and 36, are exactly the same as those described in the form shown in Figs. 1 to 3.

The operation of the parts will now be briefly described:

The air being exhausted from the wind chest 19 and a perforation from the usual note sheet uncovering a perforation in the tracker bar 25, the valves will be operated in the usual and well-known manner, so that the duct 23 or 24 will be thrown into communication with the exhaust chamber in the chest 19. The pneumatics 27 or 28 will now be exhausted and will collapse, the striker arms 35 or 36 attached to the movable leaves thereof, causing the contact buttons 36 to be carried upwardly, which will move the wippen about its pivot 15 and

through the jack 13 cause the piano hammer 10 to deliver a blow on the string 14. While I have shown and described a preferred embodiment of my invention, it is to be understood that I am not to be limited to the exact details shown, for my device is susceptible of various changes and modifications which will lie within the spirit of the invention and within the scope of the appended claims.

10 It is apparent that, due to the resiliency of the metal of which the striker arms are made, the parts of the piano action are not subject to sudden strains and stresses, and 15 the blows of the hammers on the strings are more nearly like those resulting from the human touch on the keys.

What I claim is:

1. A striker pneumatic including a movable leaf and a flexible striker arm secured thereto, said arm maintaining itself in a flexibly adjusted position in the direction of its movement.

2. A striker pneumatic including a movable leaf and a flexible striker arm secured thereto, said arm being bendable into and adapted to maintain itself in different positions of adjustment in the direction of its movement.

3. A striker pneumatic including a movable leaf and a flexibly adjustable striker arm secured thereto, said arm having a portion extending along and attached to the movable leaf of the pneumatic, and a portion projecting beyond the movable leaf for contact with a piano action, said last named portion being adjustable in the direction of the movement of the pneumatic to vary the relative positions of the two portions of the striker arm.

4. A striker pneumatic having a fixed leaf and a movable leaf hinged thereto adjacent one of its edges and a metal striker arm having a portion secured to the movable leaf of the pneumatic adjacent the free edge thereof and a portion projecting beyond said movable leaf and bent at an angle to said first portion to extend across the face of the pneumatic to a point beyond the fixed leaf thereof, and there being again bent to

extend toward the pneumatic and provide a striking surface to contact with the piano action.

5. A striker arm for attachment to the movable leaf of a striker pneumatic, said arm comprising two substantially parallel end portions one of which is adapted to be secured to the pneumatic and an intermediate portion arranged at a substantial angle to said end portions to position the latter in spaced plane, said end portions extending in the same direction from said intermediate portion.

6. A striker arm for attachment to the movable leaf of a striker pneumatic, said arm comprising an intermediate portion and two substantially parallel end portions, said intermediate portion being obliquely disposed relatively to the end portions to cause the latter to be disposed in spaced offset positions.

7. A striker arm for a striker pneumatic comprising a strip of metal having its end portions bent in the same direction from, and at oblique angles to, the body portion to lie in substantially parallel spaced planes.

8. In a player piano, a pneumatic player action including a plurality of tiers of striker pneumatics with striker arms rigidly secured to the movable leaves of said pneumatics, the striker arms of the pneumatics of the different tiers all having their striking surfaces lying substantially in one plane, and being adjustable to secure proper alignment of the striking surfaces thereof relatively to said plane.

9. In a player piano, a pneumatic player action including a plurality of tiers of striker pneumatics with metal striker arms rigidly secured to the movable leaves of said pneumatics, the striker arms of the pneumatics of the different tiers all having their striking surfaces lying substantially in one plane, and being flexibly adjustable to secure proper alignment of the striking surfaces thereof relatively to said plane.

In witness whereof, I have hereunto set my hand on the 20th day of October, 1920.

STANLEY L. FISHER.
